Des. 87

Ezra Ripley (ass' to Johnson & Cox) Troy, N.Y.
Letter Patent (Design No. 87) dated 3d October 1846

The schedule referred to in these Letters Patent and
making part of the same.

To all to whom these presents shall come:

I, Ezra Ripley of the City of Troy, County of Rensselaer and State of New York, have invented or produced, a new design for a stone plate, and that the following is a full, clear and exact dis-

scription of the same, reference being had to the accompanying drawings, marking part of this specification, in which representation, &c. &c. is a view of the plate.

The design of said plate, is of a bold, gaudy figure, and its ornaments are merely light cuts or recesses, of a diamond, round, oval & horizontal appearances. Along the top or upper edge, is a moulding of a bold ogee shape, marked a. The bottom edge is finished with a plain ogee moulding marked b, and on either edge, is a perpendicular bracket pilaster, which diminishes downward, and is divided into sections, differently ornamented, and terminates near the bottom moulding, these pilasters are marked c. In the cavity perpendicular from the bottom, and near the top of the plate, is a door with lattice work, with its margin ornamented with small RosetteS, this door is marked d; immediately under said door, is shown a panel four ornamented with the above mentioned cuts or RosetteS and a bold Rosette at each corner, said panel is marked e.

I claim as my invention, and desire to secure by Letters Patent, the above design, which is fully set forth in the drawings accompanying this description.
